[57] **CLAIM**

The ornamental design for the airline telephone handset with
digital passenger control functions and video game controls,
as shown and described.

DESCRIPTION

FIG. 1 is a first end view of an airline telephone handset with
digital passenger control functions and video game controls
showing my new design;

FIG. 2 is a second end view of that illustrated in FIG. 1;
FIG. 3 is a bottom plan view of that illustrated in FIG. 1;
FIG. 4 is a top plan view of that illustrated in FIG. 1;
FIG. 5 is a left elevation view of that illustrated in FIG. 1;
and,

FIG. 6 is a right elevation view of that illustrated in FIG. 1.
The broken line disclosure throughout the views is for
illustrative purposes only and forms of the claimed design.
